ABSTRACT

A process for the refining of metals in which a consumable electrode of the metal to be refined is melted in a vessel which comprises detecting changes in the clearance between posed surfaces of the consumable electrode and the vessel inner wall to produce a control signal to impart relative horizontal movement between the electrode and the vessel to restore the clearance.

PROCESS FOR CONTROLLING POSITION OF ELECTRODE IN ELECTROSLAG REMELTING MOLD

The present invention relates to apparatus and processes for the refining of metals and, more especially, to the secondary refining of metals.

Electroslag refining and vacuum arc remelting are examples of such processes. In the electroslag refining process, a slag within a mould is maintained in a molten state and at a temperature above the melting point of the metal to be refined. Unrefined metal is introduced into the mould and is refined as it passes in droplet form through a bath of the molten slag, refined droplets collecting to form a pool beneath the slag bath. The mould walls and base plate are cooled by the circulation of a coolant, normally water, and a solidified ingot is built up beneath the molten metal pool. The metal to be refined may be introduced to the mould in the form of a consumable electrode and the slag maintained molten by passage of an electric current from the electrode to the base plate of the mould.

To prevent excessive heat loss in the electroslag refining process the clearance between the inner side wall of the mould and the surface of the consumable electrode should not be excessive. To avoid damage to the mould wall, contact between the opposed surfaces of the mould and the electrode should be prevented.

In accordance with one aspect of the invention, a process for the refining of metals in which a consumable electrode of the metal to be refined is melted in a vessel, such as a mould, comprises detecting changes in the clearance between opposed surfaces of the consumable electrode and the vessel inner wall to produce a control signal to impart relative horizontal movement between the electrode and the vessel to restore the clearance.

Reductions in the clearance may be detected by three or more electrically activated probes which are spaced evenly around and extend inwardly from the vessel inner wall to define the desired minimum clearance between the vessel inner wall and the electrode and which are activated by contact with the electrode. Activation of one probe or of two adjacent probes may cause a control signal or signals to be passed to drive means operable to impart relative horizontal movement between the electrode and the vessel. The drive means may comprise electrical motors each connected to receive a signal from one of the probes and each operable to impart relative movement between the electrode and the vessel in such a horizontal direction as to de-activate the probe to which a respective motor is connected. Each probe may be movable towards and away from the electrode.

In accordance with another aspect of the invention, there is provided a process for the refining of metals in which a consumable electrode of the metal to be refined is positioned in a predetermined spaced relationship to a mould, the process including the steps of detecting any relative movement in a horizontal direction between the electrode and the mould, producing a signal indicative of the direction and extent of said relative movement and using said signal to operate one or more motors to cause relative movement between the electrode and the mould to return the electrode and mould to the predetermined spaced relationship.

In accordance with a further aspect of the invention, apparatus for the refining of metals comprises an electrode and means to locate the electrode in a predetermined spaced relationship to a vessel, such as a mould, the apparatus including means to detect departure from said predetermined spaced relationship and means to cause relative movement between the vessel and the electrode so as to restore said relationship. The means to detect departure from said relationship may comprise sensing probes adapted to be contacted by the electrode and thus to set up electrical signal to operate electrical motors arranged to cause relative movement between the electrode and the vessel. Four electric motors may be spaced around the periphery of a trolley carrying the vessel, the motors being so arranged that one pair of motors will move the trolley in one direction and the other pair of motors will move the trolley in a direction at right angles to said one direction.

In accordance with a still further aspect of the invention, apparatus for the refining of metals comprises a mould, means for mounting a consumable electrode therein, three or more electrically activated probes spaced evenly around and extending inwardly from the inner wall of the mould to define the desired minimum clearance between the mould inner wall and the electrode when in position, and drive means connected to receive signals from the probes when activated by contact with the electrode and operable to impart relative movement between the mould and the electrode to move the probes out of contact with the electrode.

In the accompanying diagrammatic drawings,

FIG. 1 is an elevational view, partly in section, of electroslag refining apparatus embodying the invention;

FIG. 2 is an underneath plan view of the trolley illustrated in FIG. 1;

FIG. 3 is a section in the line III—III of FIG. 1 to an enlarged scale;

FIG. 4 is a plan view of a detail of electroslag refining apparatus embodying the invention;

FIG. 5 is a section in the line V—V of FIG. 4;

FIG. 6 is a view similar to FIG. 1 showing the electroslag refining apparatus in a modified embodiment; and

FIGS. 7 and 8 are, respectively, plan and elevational views of further electroslag refining apparatus embodying the invention.

In FIGS. 1 to 3, apparatus for the electroslag refining of metal includes an open-ended mould 1 supported by a carriage 2 movable vertically relatively to a mast 3. A consumable electrode 4 is clamped in an electrode holder 5 which is movable vertically relative to a mast

55 6. Initially, the mould is mounted on but insulated from a cooled base plate 7. As the refining process proceeds an ingot is built up on the base plate 7 and the carriage 2 raised so that the base plate 7 supports the formed ingot 8. The base plate 7 and mast 3 are mounted on a trolley 9 movable in horizontal directions by electrical motors, e.g. servomotors, 10a to 10d (FIGS. 2 and 3). Servomotors 10a to 10d are, respectively, operable to move the trolley 9 in the directions indicated by arrows 11a to 11d. The electrode 4 and the base plate 7 are connected to a source of alternating current. The slag bath and metal pool are indicated, respectively, at 13a and 13b.

Sensing probes 12a, 12b, 12c, 12d are evenly spaced around the upper open end of the mould 1 and together define the desired clearance between the electrode and the inner mould wall.

The probes 12a, 12b, 12c, 12d are, respectively, connected to relays 14a, 14b, 14c, 14d which, when actuated, energise the respective servomotors 10a, 10b, 10c, 10d.

In operation, droplets of unrefined metal pass from the electrode 4 and collect in a pool below the electrically conductive refining slag. These droplets solidify to form the ingot 8. As the ingot builds up, the mould 1 is raised by the carriage 2 to maintain a predetermined distance between the level of the molten metal pool 13b and the lower open-end of the mould. Due to irregularities in the surface of the consumable electrode or to misalignment of the electrode relative to the mould, movement of the mould relative to the electrode may cause the clearance between the electrode and an adjacent surface of the mould inner wall to become less than the predetermined distance. In this event, one or two adjacent probes 12a - 12d are contacted by and receive a voltage signal from the electrode, which signal actuates the corresponding relay or relays 14a - 14d to energise the corresponding servomotor or servomotors 10a - 10d. The servomotor(s) operates to move the trolley 9 and, consequently, the mast 3 and the mould 1 in such a direction that the activated probes 12a - 12d are moved out of contact with the adjacent electrode surface. When contact between the probe(s) and the electrode is severed, the motor(s) is or are de-energised and movement of the trolley 9 is stopped.

A second array of probes 18a to 18d (FIG. 3) may be provided to allow for regular increases in electrode cross section. If such an increase should occur, all four probes 12a to 12d are simultaneously energised, whereupon they are all retracted by a motor (not shown) to positions adjacent the mould inner wall. The minimum permissible clearance between the electrode and the mould inner wall is now defined by probes 18a to 18d, which probes are spaced evenly around and fixed to the mould upper end. In an alternative arrangement, the probes are in contact with the electrode. Once this position has been reached, the motor retracting the probes is switched off and the respective servomotors operated to re-align the mould relative to the electrode until all of the probes 12 are de-energised. As previously described with reference to probes 12a to 12d, should the electrode 4 contact one or two adjacent probes 18a to 18d, the corresponding servomotor or servomotors 10a to 10d is or are operated to move the trolley 9 and, consequently, the mould 1 to a position in which an even clearance exists between the electrode and the mould. However, should more than two probes 18a to 18d be activated at any one time, a switch is thrown to sound an alarm and/or to switch off the melt power and the electrode drive.

The position of each probe 12a - 12d may be externally adjustable relative to the mould. That is to say, each probe may be moved towards and away from the electrode during a melt to accommodate general variations in electrode cross section. As illustrated in FIGS. 4 and 5, each probe 12 has a screw-threaded portion 19 which co-operates with an internally-threaded sleeve 20 mounted on a collar 21 supported on the upper end of the mould wall. The probes may be extended periodically towards the electrode until they make contact

with it and the distances moved recorded to give readings of the ratio of electrode to mould diameter.

Each probe may extend inwardly from the mould inner wall and three or more probes may be employed. 5 For example, eight evenly spaced probes may be employed, each probe being connected through a relay to a servomotor.

In the embodiment illustrated in FIG. 6, the mast 6 is movable in horizontal directions by the motors 10a to 10d, the mast 3 and base plate 7 being immobile. In this embodiment, contact of the electrode with one or two of the probes 12a - 12d or 18a - 18d causes energisation of the servomotor(s) 10a to move the mast 6 and, consequently, the electrode 4 in such a direction that the activated probes are moved out of contact with the adjacent electrode surface.

In the embodiment illustrated in FIGS. 7 and 8 the position of the electrode 4 within the mould 1 is sensed by means of four pivotable probes 20 which bear against the adjacent surface of the electrode 4. Each probe 20 is connected by an arm 21 to a member 22 which pivots with the respective probe 20. The members 22 connected to opposed probes 20 are interconnected by means of pivotally mounted links 23, 24 which are urged together by a spring 25. The links 23, 24 are coupled by an arm 26 which carries a rod 27 which is movable vertically within a bearing 28 and which can move sideways into contact with switches 29, 30. The switches, when actuated, energise respective servomotors operable to move the mould 1 in a similar manner to the servomotors 10a - 10d hereinbefore described.

In this embodiment, misalignment of the electrode causes the probes 20 and the respective members 22 to pivot, thus moving one or both of the rods 27 to one side to make contact with and actuate either switch 29 or switch 30. Actuation of switch 29 or switch 30 energises the respective servomotors to move the mould 1 in such a direction that the pivoted probes are returned to their original positions. When the probes have returned to their original positions, each rod 27 is moved to its original position out of contact with either switch 29 or switch 30 and the or each motor is de-energised and movement of the mould is stopped.

Regular changes in electrode diameter cause all probes 20 to pivot in equal amounts and the rods 27 to move upwardly or downwardly within the bearings 28.

50 Whilst the invention has been described with reference to the melting of electrodes of circular cross-section, the invention is equally applicable to processes in which electrodes of square, rectangular or other cross-section are employed.

55 I claim:

1. A process for the refining of metals in which a consumable electrode of the metal to be refined is melted in a vessel, which process comprises detecting changes in the clearance between opposed surfaces of the consumable electrode and the vessel inner wall by means of at least three pivotally mounted probes which bear against the adjacent surface of the electrode and which pivot to actuate control means operable to cause drive means to impart relative horizontal movement between the electrode and the vessel to restore the clearance.

2. A process according to claim 1 wherein two or more pairs of pivotally mounted probes are provided,

the probes of each pair being positioned to bear against opposed surfaces of the electrode.

3. In a process for the refining of metals in which a consumable electrode of the metal to be refined is positioned in a predetermined spaced relationship to the mould, the steps of detecting relative movement in a horizontal direction between the electrode and mould by means of at least three probes which are spaced around and extend inwardly from the vessel inner wall to define a predetermined minimum clearance between the vessel inner wall and the electrode and which are

activated by movement of the electrode relative to the mould in a direction which reduces the clearance therebetween to a value less than the predetermined minimum clearance, producing on activation of at least one of said probes a signal indicative of the direction of said relative movement, and using said signal to actuate control means to effect relative horizontal movement between the electrode and the mould to return the electrode and mould to their predetermined spaced relationship.
